UNITED STATES PATENT OFFICE.

GRANVILLE G. CRABB, OF LOUISVILLE, KENTUCKY.

EXTENSION-LADDER.

No. 922,091.

Specification of Letters Patent.

Patented May 18, 1909.

Application filed June 25, 1908. Serial No. 440,319.

To all whom it may concern:

Be it known that I, GRANVILLE G. CRABB, a citizen of the United States, residing at Louisville, in the county of Jefferson and 5 State of Kentucky, have invented a new and useful Improvement in Extension-Ladders, of which the following is a specification.

This invention relates to an extension step 10 ladder, the object of the invention being a ladder in which the extension will form the support for a step ladder when the device is used as an ordinary step ladder.

The invention consists in the novel features of construction hereinafter described, 15 pointed out in the claims, and shown in the accompanying drawings, in which—

Figure 1 is a perspective view showing the device in position for use as a step ladder. Fig. 2 is a front view showing a portion of the ladder with the extension in position for use. Fig. 3 is a longitudinal section through the upper portion of the device with the parts in position for use as a 25 step ladder. Fig. 4 is a section on the line 4—4 of Fig. 2.

In constructing my ladder, I employ a step section 1 and a supporting extension section 2 which ladder is provided with the 30 usual rounds 3. Upon the step ladder portion 1 and adjacent its upper end are placed plates 4 provided with inwardly extending pins 5, and upon the upper ends of the side members of the ladder section 2 are secured 35 bearings 6 in which said pins rest, the section 2 being thus pivotally connected to the step section 1. A locking bail 7 is pivotally connected to the step section and is bent to form a hook member for engagement with 40 the uppermost round 3. Angled catches 8 are pivotally connected to the outer sides of the side members of the step section 1 adjacent their upper ends, said plates being adapted to be swung over the upper ends of 45 said side members for a purpose which will appear hereafter. A bucket supporting shelf 9 is provided with angled strips 10, and said shelf is placed in position by engaging said strips 10 with the catches 8, the 50 free end portions of said strips slipping between the angled end portions of the catches and the rear faces of the side members of the step section, as shown most clearly in Fig. 2.

55 When the device is used as a step ladder section 2 forms a supporting leg for the

same and is locked in position by engagement of the bail 7 with one of the rounds 3. When the section 2 is to be employed as an extension of the ladder the shelf 9 is removed, and the catches 8 are lifted up so that their angled end portions will rest above the upper ends of the side members of the step section, and the extension is then swung upwardly into alignment with the 60 step section, the side members of the section 2 resting within the side members of section 1, as shown in Figs. 2 and 4, and angled plates 11 carried by the side members of the extension section 2 bear against 65 the rear faces of the side members of the step section, and prevent additional swinging movement in a forward direction of the extension section. The catches 8 are then turned down into their normal positions and 70 fit over the projecting angled portions of the plates 11, and lock the extension against movement toward its normal supporting position. The extension is thus locked in alignment with the step section and the ladder is used in the usual way by placing in 75 position against the wall of a building or against any other suitable support for it.

Having thus fully described my invention, what I claim as new and desire to secure by 85 Letters Patent, is:—

1. A device of the kind described comprising a step section, and an extension section, the side members of the extension section being pivotally connected to the inner 90 sides of the side members of the step section and at points below the upper ends of said side members, angled catches pivotally carried by the upper end portions of the side members of the front section, and angled 95 plates carried by the side members of the extension section, said plates engaging the side members of the step section when the extension section is lifted into position, and the said catches turning over said angled 100 plates and locking said extension in elevated position.

2. A device of the kind described comprising a step section, a supporting section pivotally connected thereto, angled, pivoted 105 catches carried by the outer faces of the side members of the step section, said catches turning up over the upper ends of said side members, a shelf, metal strips carried by the shelf and having free end portions fitting 110 between said catches and the step section, and angled plates carried by the supporting

section, said plates engaging the step section when the supporting section is lifted into alignment with it, the catches engaging said angled plates.

5 3. A device of the kind described comprising a step section, a supporting extension section, said extension section being provided with rounds, a bail carried by the step section for engagement with a round of the
10 extension section, angled stop plates carried by the extension section and limiting move-

ment of said section when swung upwardly into alignment with the step section, and angled catches carried by the step section, said catches fitting over said stops preventing reverse movement of the extension section after it has been swung upwardly into alignment with the step section. ¹⁵
